UNITED STATES PATENT OFFICE.

JOSEPH L. SANDLER, OF NEWARK, NEW JERSEY, ASSIGNOR TO THE HELEN MANUFACTURING CO., INC., OF NEWARK, NEW JERSEY, A CORPORATION OF NEW JERSEY, AND LOWENSTEIN-SANDLER & SIEGEL, INC., OF NEWARK, NEW JERSEY, A CORPORATION OF NEW JERSEY.

DESIGN FOR A MAN'S ENGAGEMENT RING.

Application filed January 18, 1927. Serial No. 20,421. Term of patent 7 years.

To all whom it may concern:

Be it known that I, JOSEPH L. SANDLER, a citizen of the United States of America, residing at Newark, in the county of Essex and State of New Jersey, have invented a new, original, and ornamental Design for a Man's Engagement Ring, of which the following is a specification, reference being had to the accompanying drawing, forming a part hereof.

In the drawing:

Figure 1 is a plan view of a man's engagement ring showing my design,

Fig. 2 is an edge view, and

Fig. 3 is a side view of the same.

The beveled marginal edges of the ring mounting are inscribed as indicated in dotted lines in Figure 1.

I claim:

The ornamental design for a man's engagement ring, as shown and described.

JOSEPH L. SANDLER. [L.S.]
